(Cl. D3—13)

To all whom it may concern:

Be it known that I, Samuel Harfenist, a citizen of the United States, residing at New York, in the county of New York and State of New York, have invented a new, original, and ornamental Design for a Raccoon Cap with Raccoon Tail, of which the following is a specification, reference being had to the accompanying drawing, constituting a part hereof:

Fig. 1 is a top plan view of a raccoon cap showing my new design.

Fig. 2 is a side elevational view.

Fig. 3 is a side elevational view of the opposite side.

Fig. 4 is a front elevational view.

I claim:

The ornamental design for a raccoon cap with raccoon tail, substantially as shown.

SAMUEL HARFENIST.
